ATTORNEY,

UNITED STATES PATENT OFFICE.

HENRY J. PALMER, OF BROOKLYN, NEW YORK.

ELECTRICAL RAILWAY SIGNALING APPARATUS.

SPECIFICATION forming part of Letters Patent No. 399,155, dated March 5, 1889.

Application filed February 18, 1888. Serial No. 265,061. (No model.)

To all whom it may concern:

Be it known that I, HENRY J. PALMER, a citizen of the United States, residing at Brooklyn, in the county of Kings and State of New York, have invented certain new and useful Improvements in Electric Railway Signaling Apparatus; and I do hereby declare that the following is a full, clear, and exact description of my invention, such as will enable others skilled in the art to which it appertains to make and use the same.

My invention has reference to improvements in electric railway signals; and it consists, more especially, in providing a system which is adapted to give automatically an audible signal upon the locomotive, the giving of such a signal depending upon the condition of a circuit or series of circuits external to the cab or locomotive and connected with extra insulated conductors along the railway-track, with which brushes or other suitable devices upon the locomotive make connection successively.

The audible signal is designed to be a danger-signal, and the absence of any signal will indicate the absence of danger along the line.

The element of safety in the use of my system is that the signal is arranged to be sounded when any one of the circuits along the line is open. This avoids the danger of a break in one of such circuits being overlooked, as such a break will, in the working of my system, be detected and serve to warn the engineer of some sort of trouble or danger, the exact nature of which can be determined afterward.

It is now generally agreed that the use of visual signals alone for giving information to an engineer is inadequate, and that it is necessary to provide such a signal as will attract the attention of the engineer under any of the conditions to which such an officer is liable to be exposed. For this reason I have provided an audible signal, which will be either a bell located in the cab of the locomotive or a whistle pitched to a shriller key than the ordinary locomotive-whistle. In practice I divide the track which is to be provided with my system and apparatus into sections and arrange in pairs between the rails of each section insulated conductors, to which electric circuits are joined. The arrangement is such that when a locomotive provided with my

brush passes over the track it automatically opens the track or external circuits upon its own section, so that a train following immediately behind it would be warned of danger. On passing to the next section, or some succeeding section, the same locomotive will automatically reclose the circuits which it has opened, and will therefore cause no signal upon a locomotive following at a proper distance. The result is that no two trains running in the same direction can approach each other nearer than the length of one, two, three, or more sections, according as the system may be arranged, without the engineer of the rear train being warned of danger. I may connect the terminals of one or more of the external circuits with one of the bolts of a draw-bridge, or with a switch, or a culvert, or any part of the road where there is a special reason to expect danger, in such a manner that when the structures are in their normal condition such external circuits shall be closed, and when the danger that is feared intervenes the circuit shall necessarily be broken. In such a case the occurrence of an accident which would endanger a train may be signaled to any suitable distance from the location where the accident takes place, and the train may be stopped. Moreover, in a case of sudden accident, where it becomes necessary or desirable to signal an approaching train and where there is not time enough for a flagman to give such signal, I provide means whereby a signal can be sent by a manual rupture of one of the circuits connected with one pair of the conducting-rails.

I have illustrated my invention in the accompanying drawings, in which—

Figure 1 is a diagram of the circuit external to the locomotive and the track apparatus. Fig. 2 is a diagram forming, practically, a continuation of Fig. 1. Fig. 3 is a diagram of the circuits on the locomotive, giving details of the brushes and their connections. Fig. 4 is a detail, and Fig. 5 illustrates a circuit-closer which I may use in connection with system.

Referring to Fig. 1, A is railway-track, and B C D E are different sections thereof, each section being provided at suitable intervals with conducting-rails a' , b' , &c., arranged in pairs between the ordinary running-rails

of the track. These conducting-rails are insulated from each other. It will be seen that the rails $a\ a'$ form the terminals of a circuit which passes through armature k and front stop, k' , and of an electro-magnet, K, while the rails $b\ b'$ form the terminals of a circuit that is closed through an electro-magnet, L. The circuit of the magnet K passes, it will be observed, through the magnet M, opposite section D, to the conductor f , and in the other direction to the conductor f' . Passing to the conductors $c\ c'$ and $d\ d'$, the connections are similar to those of the conductors just mentioned. These conductors bear the same relations to the magnets N O P that the conductors last described bear to the magnets K, L, and M. There are similar connections also for the magnets Q and R, and also for the magnets S and T, as shown in Fig. 2.

Now it is evident that if all the armatures are on the front stops of the magnets S K N Q R, &c., that all the circuits connected with the supplementary rails will be closed outside the cab of the locomotive. The circuits within the locomotive are illustrated in Fig. 3, U and V in that figure being the brushes which make contact with the conducting-rails already referred to. These brushes are pivoted in a frame, W, which is secured to the bottom of the locomotive by any suitable means. The brushes are metallic and held in metallic heads, which are secured to non-conducting posts $u\ v$, being thus insulated from each other. On the top of the post u is secured a metallic head, X, which is cut away centrally, the cut-away portion being filled with insulating material on which a spring, Y, rests when the brush-post is in a vertical position. The posts assume this position when free, being held there by the springs $u'\ v'$. When the brushes come into contact with the conducting-rails, the posts are tilted, and at that time the spring Y comes into contact with the metallic portion of the head X.

Such is the mechanical construction of the brushes and the parts immediately connected therewith. The circuits run from the brushes to the battery Z on the locomotive, the circuit from one brush passing through an electro-magnet, o. The circuit from the head X passes to one pole of the same battery through an electro-magnet, p, while the circuit from the spring Y passes to the other pole of the battery through the armature o' and the back stop, o^2 , of the magnet o. The bell q is joined on one side to the battery and on the other to the front stop of the magnet P, whose armature is joined to the other pole of the battery.

The operation of the parts described is as follows: Suppose a train to be moving toward the left in Fig. 1, with a locomotive having applied to it the apparatus shown in Fig. 3, when the brushes come into contact with a and a' , if the external circuit is closed in the manner indicated in Fig. 1, a circuit will be formed for the battery Z through the magnet

o , causing that magnet to be energized so as to attract its armature. This action serves to break connection between o' and o^2 . Accordingly, when the head X is moved over into contact with spring Y the circuit of which those parts form terminals is broken at $o'\ o^2$, and no connection takes place at magnet p. It being evident that the energization of the said magnet p is what closes the bell-circuit for sounding a signal, it is thus also evident that no signal will be sent in the conditions of things just described. Suppose, however, that the external circuit had been found broken or open from any cause, the battery would have found no circuit through o , and accordingly the armature o' would have remained against the stop o^2 under the influence of this retractile spring. In that case the circuit of battery Z would have been closed by the head X coming into contact with the spring Y, the magnet P would have been energized, and the bell-circuit completed, causing a sound of warning to the engineer. Now, every engine that is provided with my apparatus on proceeding farther along the section until it comes, for example, to the position where its brushes are in contact with $b\ b'$, does break the circuit running from $a\ a'$ by energizing the magnet L and tilting the armature between L and K over to the side of L. Therefore, if a following engine comes along before the first has left section A, it will find the external circuit first described open, and will receive a warning of danger. The same thing happens at every section. When, however, the train has gone far enough beyond the point where it opened the original circuit to be out of dangerous proximity to a train coming behind it, it closes the external circuit through the magnet K, and restores the circuit, so that a train coming along will find the apparatus set to "safety." In the present instance I show the terminals of the magnet K connected to ff' ; but it is obvious that I might carry them still farther along, so as to maintain a greater "safety" distance between trains running in the same direction. Moreover, it is obvious that any two conducting-rails forming a pair, as $g\ g'$, for example, might be connected to a bolt of a draw-bridge or to a culvert or other railway structure in such a manner that when the bolt was withdrawn or the culvert broken the circuit might also be ruptured and a warning of "danger" thus given.

In place of the bell q, I may put a whistle of shriller tone than the ordinary railway-whistle, in which case the circuit controlling the whistle should normally be kept closed and the movement of the armature of magnet P should open the said circuit and release a valve to allow the whistle to blow. This, however, is a matter of detail. In this case the spring Y would normally rest on conducting material.

In Fig. 4 I show a pair of conducting-rails, $a\ a'$, mounted upon a common insulating sup-

port. This support may be of wood or any other good insulating material.

Fig. 5 shows a circuit-closer having a special object. The device consists of a roller, *l*, 5 mounted in a yoke which is attached to a suitable support, *m*. A shaft, *m'*, passes through a slot in this support and serves as the axis of two disks or rollers on opposite sides thereof. Each of these disks rests upon a spring, 10 as *n'*, one of these springs being a circuit-terminal located at a short distance from the corresponding terminal, *l'*. These terminals are connected, as will be seen, with the circuit of a local battery, *z*, which is external to the 15 locomotive, and which includes the magnet *L*.

There is the same arrangement in connection with the magnet *O*, *M*, and *P*, and so on. The object of this arrangement is to provide means whereby a tramp-engine which may 20 come along unprovided with my locomotive apparatus may set a "danger" signal, so as to keep engineers on the look-out. The roller *l* is arranged in such a position that it will necessarily be set by a passing engine and set 25 the signals to "danger."

The magnets at the left of the armatures in Fig. 1 may be regarded as danger-magnets, while those at the right may be called "safety magnets."

30 In place of the extra rails arranged in pairs, as I have described, I may insulate opposite rails of the ordinary track and utilize them in the same way.

Having now described my invention, what I 35 claim is—

1. In an electric railway signaling system, track-terminals and a partial electric circuit

connected therewith, corresponding train-terminals and a partial circuit connected therewith and passing to a battery on the train 40 through an electro-magnet, in combination with a separate circuit controlling a signaling apparatus through the armature and back stop of the said magnet, the said separate circuit being normally open between two points, 45 but closed at those points when the contact devices on the train are upon the road-terminals, whereby, if the external circuit be found closed, a signal upon the locomotive will be prevented, and if found open a signal 50 will be sounded, as and for the purpose set forth.

2. The combination, with conducting-rails along a railway-track, of corresponding contact devices upon a train, the said devices being attached to one or more movable or tilting supports, and a circuit-controller operated directly by the movement of said tilting supports to close a circuit upon the train, as and 55 for the purpose set forth.

3. The combination, with the contact-brushes and the supporting-frame in which they are pivoted, of the battery *Z*, the partial circuit containing the magnet *o*, and the secondary circuit controlled by the said magnet 60 and having as its terminals the head *X* and the spring *Y*, as and for the purpose set forth.

In witness whereof I have hereunto signed my name in the presence of two subscribing witnesses.

HENRY J. PALMER.
